UNITED STATES PATENT OFFICE.

WILLIAM F. McCARTY, OF DEFIANCE, OHIO, ASSIGNOR TO DEFIANCE MACHINE WORKS,
OF DEFIANCE, OHIO, A CORPORATION OF OHIO.

MEANS FOR LUBRICATING MACHINE-TOOLS.

1,337,981.

Specification of Letters Patent. Patented Apr. 20, 1920.

Original application filed February 15, 1918, Serial No. 217,358. Divided and this application filed January 24, 1919. Serial No. 272,961.

To all whom it may concern:

Be it known that I, WILLIAM F. McCARTY, a citizen of the United States, and a resident of Defiance, in the county of Defiance and 5 State of Ohio, have invented a new and Improved Means for Lubricating Machine-Tools, of which the following is a full, clear, and exact description, this being a division of the application for Letters Patent of the 10 United States for a drill press, Serial No. 217,358, filed by me February 15, 1918.

The object of the invention is to provide a new and improved means for lubricating the drill spindle, the driving and feeding 15 mechanisms for the drill spindle, the speed changing mechanism for the said driving and feeding mechanisms and simultaneously supplying lubricant to the drilling tool in the work on the work bed. Another object 20 is to insure a continuous feeding of the lubricant for both purposes above mentioned and while the drill press is running. Another object is to permit of using the lubricant over and over again thus reducing the 25 waste of the lubricant to a minimum. Another object is to permit the use of a completely closed casing or frame to prevent the entrance of dust and other extraneous matter and to prevent the attendant from becoming 30 entangled in the moving parts.

With these and other objects in view, the invention consists of certain novel features of construction as hereinafter shown and described and then specifically pointed out 35 in the claims.

A practical embodiment of the invention is represented in the accompanying drawings forming a part of this specification, in which similar characters of reference indicate 40 corresponding parts in all the views.

Figure 1 is a side elevation of a drill press provided with the improved lubricating means, a portion of the casing being shown in section;

Fig. 2 is a sectional front elevation of the lubricating means; and

Fig. 3 is a sectional side elevation of the same.

The drill press provided with the lubricating means is mounted on a hollow main frame or casing 30 supported on a suitable base 31, and on the said casing 30 is mounted to slide up and down a work bed 33 adapted to support the work to be drilled by a drill-

ing or reaming tool 34 removably attached 55 in the usual manner to the lower end of a drill spindle 35 mounted to turn and to slide up and down in suitable bearings arranged in the head 36 of the casing or main frame 30. Within the casing 30 is mounted a 60 driving mechanism 50 for driving the spindle 35 and a feed mechanism 51 is also mounted in the casing for feeding the drill spindle 35 up and down. Within the casing 30 is further mounted a speed changing 65 mechanism 52 connected with the mechanisms 50 and 51 to actuate the same, and the said speed changing mechanism 52 is driven from the main shaft 53 journaled in the lower portion of the casing 30. 70

In order to supply a lubricating oil to the drilling tool 34 in the work on the work bed 33 the following arrangement is made: In the lower portion of the main frame 30 is mounted a rotary pump 320 having its suction pipe 321 extending into an oil well 322 formed in the base 31. The outlet pipe 323 of the pump 320 extends through one side of the casing 30 to the outside thereof, and the outer end of this outlet pipe 323 is coupled to one end of a hose 324 coupled at its other end to a vertical shank 325 of a faucet 326 having its discharge spout 327 adapted to deliver the oil to the work and to the drilling tool 34. The shank 325 of the 85 faucet 326 is held vertically adjustable in a clamp 328 arranged on the work bed 33 (see Fig. 3) so as to move up or down with the same, the flexible hose 324 permitting such movement. When the pump is running 90 oil is pumped from the oil well 322 to the faucet 326, the spout 327 of which directs the oil to the drill hole. When it is desired to stop the oil feed the operator closes the faucet 326 without stopping the pump 320, 95

which latter is provided with a supplementary outlet pipe 329 discharging the oil back into the oil well 322. The drip oil from the work passes into a drip pan 330 forming part of the work bed 33 and from 100 the bottom of this drip pan 330 extends a hose 331 which discharges into a pan 332 forming part of the base 31 and arranged above the oil well 322 with which it is connected by a sieve or strainer 333 so that 105 the drip oil is drained prior to passing back into the oil well 322.

In order to supply lubricating oil to the

drill spindle 35 and to the mechanisms 50, 51 and 52 mounted on the casing 30, the following arrangement is made: A pump 340 is arranged adjacent the pump 320 in the lower portion of the casing 30, and the suction pipe 341 of this pump extends into an oil well 342 arranged in the casing 30. The outlet pipe 343 of this pump 340 extends upwardly and terminates in a discharge spout 344 terminating at the top of the drill spindle 35 to deliver oil to the top of the drill spindle. The oil thus delivered at the highest point of and within the casing 30 can readily pass to the various devices to properly lubricate the same, it being understood that the oil readily flows by its own gravity downward and is readily distributed by the rotating parts from one device to another so as to properly lubricate the same, it being understood that a portion of the oil eventually passes into the housing 54 by way of its open top to lubricate the speed changing device 52 mounted in the said housing and which latter forms part of the casing 30.

The pump 340 is provided with a branch pipe 346 terminating in a faucet 347 adapted to discharge oil into the oil well 322 whenever the faucet 347 is opened and the feed of the oil to the different mechanisms is stopped. The pipe 343 can also be drained of its lubricating oil by way of the faucet 347 in case a change in the lubricating oil is contemplated.

The two pumps 320 and 340 are simultaneously driven from the main shaft 53 and for this purpose the left hand end of this main shaft is provided with a gear wheel 350 in mesh with a gear wheel 351 attached to the shaft of the pump 340. The gear wheel 350 is in mesh with a gear wheel 352 on the shaft of the pump 320 to rotate the pumps in unison. It is understood that when the drill press is running the oil pumped by the pump 340 and discharged by the nozzle 341 onto the upper end of the drill spindle can readily lubricate the latter and the several mechanisms mounted in the casing 30. It will also be noticed that simultaneously with delivering oil to the drill spindle the oil is delivered by the spout 327 to the drill hole in the work. It will further be noticed that by the arrangement described the lubricant is used over and over again, and different lubricant may be used in the oil wells 322 and 342.

Having thus described my invention, I claim as new and desire to secure by Letters Patent:—

1. In a drill press, a main frame, a vertically disposed drill spindle mounted to turn and to slide up and down on the said main frame, mechanism imparting turning movement to the said drill spindle, mechanism imparting feeding movement to the said drill spindle, the said mechanisms and the upper portion of the drill spindle being housed in the said main frame, and a single lubricant supply having its discharge end above the top of the said drill spindle for delivering lubricant to the top of the drill spindle to lubricate the latter and to allow the lubricant to flow to the said several mechanisms to lubricate the same.

2. In a drill press, a main frame, a vertically disposed drill spindle mounted to turn and to slide up and down on the said main frame, mechanism imparting turning movement to the said drill spindle, mechanism imparting feeding movement to the said drill spindle, the said mechanisms and the upper portion of the drill spindle being housed in the said main frame, an oil well mounted on the base of the said main frame, a pump mounted on the said main frame and running in unison with the said mechanisms, the said pump having its suction pipe extending into the said oil well, the outlet pipe having a discharge spout extending above the top of the drill spindle and discharging onto the top of the drill spindle to lubricate the latter and to allow the oil to flow to the said several mechanisms to lubricate the same.

3. In a means for lubricating machine tools, the combination of a closed casing provided with an oil well adapted to contain a liquid lubricant, a vertical drill spindle having its upper part mounted in the casing, mechanisms in the casing for driving and feeding the said drill spindle and a speed changing mechanism in the casing and connected with the said driving and feeding mechanisms, and a pump arranged in the said casing and driven in unison with the said speed changing mechanism, the said pump having a suction pipe extending into the said oil well and the pump having a discharge pipe terminating at the upper end in a nozzle located above the top of the said drill spindle to discharge the oil thereon and to allow the oil to flow down and lubricate the said mechanisms in the casing and to return to the said oil well.

4. In a drill press, a lubricating means for the rotating an up and down moving drill spindle, the said lubricating means including a pump having a discharge pipe terminating in a nozzle located above the top of the drill spindle and discharging thereon whether the drill spindle is in upper, lower or intermediate position.

5. In a means for lubricating machine tools, the combination of a closed casing provided with an oil well adapted to contain a liquid lubricant, a vertical drill spindle having its upper part mounted in the casing, driving and feeding mechanisms located within the said casing for rotating the said drill spindle for moving the same up and down, the said mechanisms being located below the top of the said drill spindle, a

5 pump driven simultaneously with the said mechanisms, the pump having a suction pipe extending into the said oil well and the said pump having a discharge pipe terminating at its upper end in a nozzle located above the top of the said spindle to discharge the lubricant thereon whether the drill spindle is in its uppermost, lowermost or intermediate position, the lubricant flowing from the 10 said drill spindle to the said mechanisms and from the latter to the said oil well.

6. In a means for lubricating machine tools, the combination of a closed casing provided with an oil well adapted to contain a 15 liquid lubricant, a vertical drill spindle having its upper part mounted in the casing, driving and feeding mechanisms located within the said casing for rotating the said drill spindle for moving the same up and down, the said mechanisms being located 20 below the top of the said drill spindle, a speed changing mechanism arranged within the casing and located below the said driving and feeding mechanisms and above the said oil well, a pump driven simultaneously with 25 the said mechanisms, the pump having a suction pipe extending into the said oil well and the said pump having a discharge pipe terminating at its upper end in a nozzle located above the top of the said spindle to 30 discharge the lubricant thereon whether the drill spindle is in its uppermost, lowermost or intermediate position, the lubricant flowing from the said drill spindle to the said mechanisms and from the latter to the said 35 oil well.

WILLIAM F. McCARTY,
